UNITED STATES PATENT OFFICE.

JOHN GREENWOOD AND FRANCIS J. HELMUTH, OF NORTH CHICAGO, ILLINOIS.

DESIGN FOR A BADGE.

SPECIFICATION forming part of Design No. 29,916, dated January 3, 1899.

Application filed October 29, 1897. Serial No. 656,843. Term of patent 7 years.

To all whom it may concern:

Be it known that we, JOHN GREENWOOD and FRANCIS J. HELMUTH, citizens of the United States, residing in North Chicago, in the county of Lake and State of Illinois, have invented and produced a new and original Design for a Badge, of which the following is a specification, reference being had to the accompanying drawings, showing the said design.

In the accompanying drawings, which are made a part of this application, Figure 1 is a front elevation, and Fig. 2 a rear elevation, of our design, and these figures are deemed a full illustration of the design.

The leading and characteristic features of our design comprise the badge in its entirety, which shows the representation of a crosscut-saw A, an ax B, the maul C, and the wedge D, grouped together, as illustrated in the drawings. 20

What we claim is—

The design for a badge as herein shown and described.

JOHN GREENWOOD.
FRANCIS J. HELMUTH.
